UNITED STATES PATENT OFFICE

2,003,509

TAPPET

Stephen Jencick, Chagrin Falls, Ohio

Application November 25, 1931, Serial No. 577,354

5 Claims. (Cl. 123—90)

This invention relates to an improved form of tappet for use in an internal combustion engine.

As is well known to those who are familiar with the art to which the present invention relates, each cylinder of an internal combustion engine is provided with intake and exhaust valves which are normally closed by means of a spring surrounding the stem of each valve and which are opened and closed in properly timed relation for the intake, compression, firing, and exhaust operations. For the purpose of opening the valves, there is provided a tappet which engages the end of the valve stem in each case and which is actuated by a cam shaft so as to effect such opening of the intake and exhaust valves in proper sequence.

According to the old devices, it has been necessary to adjust the tappets so as to assume proper engaging relation between the cams on the cam shaft and the ends of the valve stems, such adjustment of the tappets being required at the time of assembly and thereafter from time to time in order to compensate for any wear or loss of adjustment otherwise between the parts. As is already well known, the lack of proper adjustment and engagement between these parts means not only lack of efficiency in operation of the valves but also a certain amount of noise. Also, such improper engagement between the tappet and the valve stem results in undue wear of these parts as well as the valves and valve sets themselves; that is, any failure of the tappet to open the valve because of lack of proper operative engagement between these parts might result in the valve sticking to its seat, and failure to permit proper intake and exhaust of the gases means failure to operate in an efficient manner and hence loss of power and smooth running of the engine.

The present invention contemplates the relief of such conditions as above briefly outlined and in a general way this invention consists in the provision of an automatically adjustable tappet which is adapted to compensate for and overcome any lack of proper adjustment and engagement between the tappet and valve stem as might otherwise occur.

More specifically, the present invention consists in the provision of an adjustable tappet which is adapted to be automatically extended and contracted as conditions may require so as to at all times maintain operative, contactual engagement between the valve stem and the tappet so as to insure efficient operation of the valve regardless of any wear between the parts and also in spite of any sticking of the valve or other

abnormal condition which might otherwise prevail and prevent efficient operation.

The present invention is so devised that the automatic contraction and extension of the tappet will be effected in a gradual manner so as to avoid any undue clash and wear between the parts.

Another object consists in devising such an automatically adjustable tappet which can be regarded as a complete unit which is capable of being installed in an internal combustion engine without requiring modification of the other parts.

A further object consists in providing such a device which can be manufactured in a comparatively simple manner and hence sold at a comparatively low price so as to render the same practical in every respect.

Other objects will be apparent from the following description and claims when considered together with the accompanying drawing.

Fig. 1 is a vertical sectional view illustrating the structure and assembly of my improved form of tappet;

Fig. 2 is a transverse sectional view taken on line 2—2 of Fig. 1; and

Fig. 3 is a vertical sectional view taken on line 3—3 of Fig. 1.

In the present illustration, there is indicated a valve 1 which is of conventional form and which is arranged in the usual manner so as to close upon the valve seat 2 provided upon the engine block 3. The valve 1 has the valve stem 4 surrounded by the coil spring 5 which has its one end abutting the engine block while its other end engages the flanged member 6 which is secured near the lower end of the valve stem 4 so as to normally force the valve 1 to closed engagement with the valve seat 2. The lower end of the valve stem 4, as usual, extends beyond the flanged members 6 so as to provide the lower projecting end portion 4a for engagement by the upper end of the tappet. As above stated, the construction thus far described is of conventional form, as is also the cam shaft 7 and the cams 8 provided thereupon; it being understood that the cam shaft is operated in the same manner as is already well known to those skilled in the art.

In my present improved form of invention, the tappet comprises the casing 9 which is flanged at its lower end 9a for engagement by the cam 8 of the cam shaft. The casing 9 is hollowed-out throughout the upper portion thereof so as to receive with a drive fit the upper part 10 which has the lower portion 11 extending within the hollowed-out portion of the casing 9. Both the

casing 9 and the upper part 10 are of cylindrical form as well as the lower portion 11 which fits within the casing 9. Thus, the parts 9 and 10 are secured together and may be considered as 5 one and the same part which may be formed as a single integral member.

The lower extending portion 11 is also hollowed-out with a cylindrical well adapted to receive and accommodate the coil spring 12 which rests in 10 the bottom of the hollowed-out portion 11 while the upper end thereof has bearing engagement with the lower end of the wedge member 13. The wedge member 13 is also of cylindrical form and is provided at its upper side with an inclined 15 surface extending approximately at an angle of 45°, as indicated in the drawing. There is provided a companion wedge member 14 which is also of cylindrical form and which has its lower side provided with a corresponding, inclined surface 20 which is adapted to engage the inclined surface of the companion member 13. The inclined engaging surfaces of the companion members 13 and 14 are of a flat or plain form so that there 25 will not be permitted any relative turning movement between these companion members. The companion member 13 is practically co-terminous with the end portion 11 and the lower part of the member 14 extends within the well portion 11, while the upper end thereof projects upwardly 30 into the enlarged upper portion of the part 10, as clearly indicated in Fig. 1.

It will be observed that the companion members 13 and 14 are so constructed that when they are in full engagement, as illustrated in Fig. 1, there is still space allowed between the extreme 35 upper end of the companion member 13 and the corresponding part of the member 14 and also between the extreme lower end of the member 14 and the corresponding part of the companion member 13. This arrangement insures effective 40 frictional engagement between these members, as will be more fully understood. It is to be understood also that the lower end of the member 13 and the upper end of the member 14 are both 45 formed with squared surfaces. Thus, these two companion members 13 and 14 may be regarded as duplicates.

The upper squared end of the member 14 is 50 adapted to engage the under side of a shoe 15 which has its upper surface curved, as indicated at 15a, so as to afford seating engagement for the eccentric member 16. The member 16 has its stub shaft 17 mounted eccentrically with respect thereto and also to one side of the longitudinal axis through the tappet assembly, as clearly 55 indicated in Fig. 1, the shaft 17 being mounted in the block 18 which is positioned within the upper enlarged hollow portion of the part 10. The bearing member 18 may rest upon a washer 60 18a which is of annular form and through which the companion members 13 and 14 extend.

The shoe 19, which is a duplicate of the shoe 18, is positioned above the eccentric member 16 so as to afford seating engagement therefor with the curved surface 19a of this shoe. It should 65 be explained that the shoe 18 is separate from the member 14 and merely has seating engagement thereupon so as to be free for a certain degree of lateral movement as is true also of the upper shoe 19, such lateral movement being 70 caused by actuation of the eccentric 16.

Engaging over the upper flat side of the shoe 19, there is provided the cap member 20 which 75 has depending, annular flange 20a extending with frictional engagement within the upper end of

upper part 10. The upper, outer surface of the member 20 is adapted for contactual engagement with the lower projecting portion 4a of the valve stem.

The several parts of the present improved form of tappet are so constructed and arranged in assembly that there is afforded not only the compression of the spring 12 but also the frictional engagement between the companion members 13 and 14 themselves over their engaging, inclined 10 surfaces as well as between the cylindrical surfaces thereof and the engaging inner surface of the well portion 11. There is further frictional engagement afforded between the outer surface of the eccentric 16 and the correspondingly curved 15 engaging surfaces of the shoes 15 and 19. Furthermore, frictional engagement is provided between the flange 20a and the inner surface of the upper end portion of the part 10 within which this flange engages and is adapted for movement. 20 Also, by virtue of the engagement between the upper end of the member 14 and the lower surface of the shoe 15, as well as between the upper surface of the shoe 19 and the inner under-surface of the member 20, there will be afforded a still 25 further degree of friction.

The friction above referred to as being afforded between the several parts of my present tappet assembly, serves as a means of resistance which is of such degree as to prevent sudden contracting movement between the parts, but at the same time there will be permitted gradual contraction in an effective manner for the purpose intended. It is to be understood also that the spring 12, although of comparatively inferior 35 strength, may be relied upon to gradually and effectively cause automatic extension between the parts and thus overcome the friction therebetween so as to produce the desired extension of the tappet at the time required.

As indicated in the drawing, the spring 12 is of comparatively smaller size and less strength than the spring 5. Assuming, for instance, that the spring 5 has a strength of approximately eighty (80) pounds, the spring 12 in my present 45 improved assembly may be of only approximately ten (10) pounds. However, the aggregate resistance offered by the combined factors of the spring 12 and the friction between the several parts, as above referred to, is somewhat in excess 50 of the degree of resistance offered by the spring 5. Thus, upon actuation of the present tappet assembly by the cam shaft, this combined resistance offered by the tappet will serve efficiently to overcome the resistance of the spring 5 so as 55 to raise the valve from its seat.

It should be explained also that the degree of rotary movement of the eccentric 16 about the axis 17 is, in the present form of device, approximately ninety degrees (90°) and, as will be seen from the very nature of the eccentric, the degree of resistance induced thereby through the frictional engagement thereof with the shoes 15 and 19 will be gradual. The practical effect of such manner of operation is that the automatic 65 adjustment of the tappet assembly in either direction is gradual so as to produce a quiet and effective operation.

Upon installation of the present tappet assembly and during normal operation of the same, 70 the spring 12 will be placed and maintained under a certain degree of compression by engagement of the tappet with the valve stem. This compression of the spring 12 is constant and substantially uniform and, as before stated, the 75

combined resistance offered by the spring 12 and the frictional resistance between the other parts is sufficient to cause opening of the valve. The position and condition of the several parts of the present assembly, as indicated in Fig. 1, correspond to normal operation, and these parts all maintain substantially the same position and condition throughout normal opening and closing movements of the valve, the entire tappet assembly functioning as a unit. It is to be understood, of course, that during such normal operation, the upper and lower ends of the tappet are in constant contactual engagement with the end portion 4a of the valve stem and the cam 15 of the cam shaft, respectively.

If, however, for any reason such, for instance, as the sticking of the valve stem in raised or open position, or wear between the parts so as to create what would otherwise be a gap between 20 the upper end of the tappet and the lower end of the valve stem, then the automatic adjustment of the tappet assembly is called into play.

Let us consider first the possible wear between the lower end of the valve stem and the upper 25 end of the tappet which, as is well known, would ordinarily cause a gap with resultant noise and lack of efficiency in the operation of the valve. Under such condition, the present tappet assembly will automatically adjust itself so as to take 30 up such wear and to always maintain contactual engagement between the upper end of the tappet and the lower end of the valve stem. In other words, any such wear which would ordinarily cause a gap between these parts will be compensated for by the automatic extension which will be produced by the force of the spring 12 between the extensible parts of the tappet assembly; and, as before explained, such extension between the parts of the tappet will be gradual by 35 virtue of the frictional engagement and the action of the eccentric 16. According to Fig. 1 of the drawing with the parts in position as there- 40 in illustrated, the expanding or extending action of the spring 12 will cause the eccentric 16 to 45 turn in a counter-clockwise direction, and such operation of the eccentric 16 will produce a gradual movement and friction between the parts.

Assuming now that the valve stem, because of 50 sticking, has caused the valve to remain in open position, ordinarily such condition would result in a decided gap between the lower end of the valve stem and the upper end of the tappet, with the objectionable result already referred to. With 55 the present form of device, the tappet will automatically extend itself by virtue of the spring 12 so as to gradually take up what would otherwise result in such a gap. In this case, as in the other case above supposed, the extending action between the parts of the tappet will be gradual 60 and the danger of any such gap will be obviated. That is, so long as the valve stem remains in abnormal raised position, the tappet assembly will continue in extended condition so as to at all times maintain contactual engagement between the 65 upper end of the tappet and the lower end of the valve stem. Continued operation of the cam shaft and engagement of the cam with the lower end of the tappet, although not effective in producing normal operation of the valve so long as the valve 70 remains stuck in open position, yet will be permitted during such abnormal position of the valve, and continued engagement of the cam with the tappet will cause more or less compression of the spring 12 which will thereby absorb such 75 motion of the cam shaft until it again becomes

effective for normal operation of the valve. Furthermore, since such automatic extension of the tappet will compensate for and overcome any such gap which might be caused, even by such abnormal sticking of the valve stem in raised position, there is thereby always maintained a constant contactual means of engagement between the tappet and the valve stem, and the intermittent engagement of the cam with the tappet will transmit therethrough to the valve 10 stem a certain degree of force which is calculated to assist in overcoming the sticking of the valve stem.

Then upon release of the sticking valve stem with the aid of the spring 5, the parts may again 15 return to normal condition, and, as already indicated, the contracting movement between the parts of the present tappet assembly will be gradual by virtue of the combined component of resistance offered by the frictional engagement 20 between the several parts as well as the force of the spring 12. This, under such condition also there is prevented any sudden movement of or 25 between the parts and thus there is insured smooth and effective engagement and operation. It is understood, that upon release of a sticking valve stem so as to permit contracting movement of the tappet, the eccentric 16 will be moved in a clockwise direction, as viewed in Fig. 1. During such automatic adjustment between the 30 parts, there will result also the same gradual and progressive increase of friction between the parts as already explained, and the spring 12 will again be placed under increased compression so as to 35 assume condition for normal operation in the manner already explained.

With the present invention, there is obviated the necessity of manually adjusting the tappet from time to time as is now required with the present form of construction and a further advantage consists in the elimination of noise between the parts. Furthermore, the present device makes possible a more efficient operation, as will be obvious to those who are skilled in the art. Finally, the structure contemplated by the present invention is of a comparatively simple nature, 40 is calculated to have longer life without renewal of parts, and may be manufactured and sold at such a price as to encourage universal adoption. 45

Other advantages will be obvious to those who 50 are skilled in the art to which the present invention relates.

What I claim is:

1. In a tappet assembly, the combination of a valve adapted to normally occupy closed position, a tappet comprising a plurality of longitudinally extensible, frictionally engaging parts with resilient means operatively associated therewith so as to permit contraction and effect automatic extension of the same respectively, 55 means having a surface of regular curvature operable as an eccentric about a center and having operative engagement with said parts for increasing the degree of friction therebetween, and means for actuating the tappet so as to open the valve and permit closing thereof, whereby there is obtained automatic adjustment of the tappet so as to maintain normal operative engagement of the tappet with the valve stem. 60

2. In a tappet assembly, the combination of a 70 valve adapted to normally occupy closed position, a tappet comprising a plurality of longitudinally extensible, frictionally engaging parts and resilient means operatively associated therewith, said parts including companion members having in- 75

terengaging inclined friction faces, the said frictional parts and resilient means being so co-related that there is permitted and effected gradual movement between said parts in contraction and automatic extension of the same respectively, and means for actuating the tappet so as to open the valve and permit closing thereof, whereby there is obtained automatic and gradual adjustment of the longitudinally extensible parts so as to maintain normal operative engagement of the tappet with the valve stem.

3. In a tappet assembly, the combination of a valve adapted to normally occupy closed position, a tappet comprising a plurality of longitudinally extensible, frictionally engaging parts and resilient means operatively associated therewith, said parts including companion members having interengaging inclined friction faces, the said frictional parts and resilient means being so co-related that there is permitted and effected gradual movement between said parts in contraction and automatic extension of the same respectively, means for actuating the tappet so as to open the valve and permit closing thereof, and eccentric means having a surface of regular curvature and having operative engagement with said parts so as to be actuated by extension and contraction of the tappet for increasing the degree of frictional engagement between the parts of the tappet, whereby there is obtained automatic and gradual adjustment of the tappet so as to maintain normal operative engagement of the tappet with the valve stem.

4. In a tappet assembly, the combination of a valve adapted to normally occupy closed position, a tappet comprising a plurality of longitudinally extensible, frictionally engaging parts with resilient means operatively associated therewith, said parts including companion members having interengaging inclined friction faces, the said frictional parts and resilient means being

so co-related that there is permitted and effected gradual movement between said parts in contraction and automatic extension of the same respectively, means for actuating the tappet so as to open the valve and permit closing thereof, and means including an eccentric having a surface of regular curvature and friction shoes adapted for engagement thereby, said means having operative engagement with said parts and being actuated by extension and contraction of the tappet for increasing the degree of frictional engagement between the parts of the tappet, whereby there is obtained automatic and gradual adjustment of the tappet so as to maintain normal operative engagement of the tappet with the valve stem.

5. An automatically adjustable tappet comprising a casing having a hollow well portion provided therein, a coil spring in said well, inversely arranged, duplicate wedge members having frictional sliding engagement with the inner surface of said well portion and having interengaging inclined faces, one of said wedge members engaging the end of said spring, a pair of friction shoes having oppositely disposed curved surfaces, an eccentric having frictional engagement between the curved surfaces of said shoes, the under side of the lower shoe engaging the end of the other of said wedge members, a cap member having slideable engagement with the inner surface of said casing and having its under surface in engagement with the upper side of said upper shoe, said parts being so constructed and arranged that the outer surface of said cap member may engage the end of a valve stem and the opposite end of said casing may be engaged by the cam of a cam shaft, and there may be automatically effected gradual contraction and extension of the tappet in accordance with the condition of valve stem.

STEPHEN JENCICK.
